DRAFTING APPARATUS

Robert F. Jessen, Lancaster, S. C., assignor, by
mesne assignments, to Saco-Lowell Shops, Bos-
ton, Mass., a corporation of Maine

Application February 25, 1947, Serial No. 730,834

4 Claims. (Cl. 19—131)

1

This invention relates to the drafting of fibrous strands in the production of yarn and is concerned more particularly with a novel apparatus for subjecting such strands to long draft.

Spinning frames containing long draft mechanisms have been in common use for some time for operation on cotton and the conventional frames of this type are restricted to the drafting of stock containing fibers of a maximum staple length, which is relatively short and approximates that of cotton. A mill equipped with such conventional long draft spinning mechanisms can, accordingly, not process fibers 2" or more in length and thus cannot handle uncut worsted fibers or synthetic fibers in the staple lengths usually employed. More recently, long draft frames designed to handle stock containing long fibers and long draft frames capable of conversion, so that they can handle either short or long fiber stock, have been available, but a mill equipped with conventional long draft mechanisms must either continue to limit its production to short fiber yarn or else scrap that equipment and, at great expense, replace it with equipment designed specially for long fiber operation, or with equipment of the convertible type.

The new drafting mechanism can be incorporated at low cost in present conventional long draft spinning frames and such frames can then be used in the drafting of fibers of much longer staple length than those which the frames were originally intended to handle. Also, the new mechanism can be quickly converted from long to short fiber operation and vice versa. Conventional long draft frames, in which the new drafting mechanism has been installed, can, accordingly, be used for the handling of either cotton fibers, synthetic fibers up to about 3" long, or worsted fibers up to about 3½" long. The apparatus offers the further advantage that yarn made from long fibers by its use is substantially stronger than that made by prior long draft equipment designed for handling such fibers.

In the new drafting mechanism, the strand to be drafted is gripped tightly by pairs of rolls having a spacing between their nips, which is substantially greater than the staple length of the fibers in the strand, the front rolls operating at a surface speed many times, for example, 18 or 20, that of the back rolls. A length of the strand lying between and spaced from the nips of the rolls and terminating close to the front rolls is supported on a traveling surface moving at a speed greater than the surface speed of the back rolls, and the fibers in the length of the strand so supported, are controlled by pressing the strand

2

lightly against that surface. Fibers gripped by the front rolls can, accordingly, be drawn forward thereby past the point of application of the pressure on the strand without damage, while those not so gripped are held back. Uniformity in drafting is obtained partly by the application of the light pressure to the supported length of the strand and partly by the contact of the strand with the supporting surface. The traveling supporting surface is provided by means of an endless apron, having a stretch extending parallel to the path of the strand, and, in order that the apron may be advanced at the proper rate, it is passed over a driven roll at the rear end of the stretch, and its edges are pressed tightly against the driven roll. The control pressure is applied to the strand over the central part of the apron above the driven roll, as well as elsewhere along the stretch of the apron lying parallel to the strand.

For a better understanding of the invention, reference may be had to the accompanying drawings, in which:

Figure 1 is a top plan view of one form of the new apparatus;

Figure 2 is a sectional view on the line 2—2 of Figure 1;

Figure 3 is a view in side elevation of a top roll employed in the new apparatus;

Figure 4 is a sectional view on the line 4—4 of Figure 3;

Figures 5 and 6 are sectional views on the lines 5—5 and 6—6 of Figure 3; and

Figure 7 is an end view of the roll shown in Figure 3.

The new drawing mechanism illustrated in Figures 1 and 2 is suitable for use on a spinning frame and includes the usual roll stand 10 provided with bearings, in which three driven bottom rolls 11, 12, and 13 are mounted. The rolls are bare and made up of sections connected end to end, so that the rolls extend the length of the frame, and rolls 11 and 13 are fluted, while roll 12 is knurled. Top rolls 14 and 15 cooperate, respectively, with front and back bottom rolls 11 and 13, and the top rolls, each of which has two bosses, are covered with any of the usual roll coverings, and have ends received in pockets in cap bars 16 attached to a shaft 17.

A plurality of top rolls 18 are mounted in alignment along the frame to cooperate with the intermediate bottom roll 12 and each top roll has two bosses and includes an arbor 19, the ends of which enter pockets in the cap bars. Collars 20 are mounted near opposite ends of the arbor

19 and are held in place by set screws 21. Midway of its length, the arbor carries a sleeve fast thereon, the sleeve being formed with a central neck 22 and enlarged hubs 23 at its opposite ends. A floating boss 24 is mounted on the arbor between each hub 23 and the adjacent collar 20 and the bosses 24 have an axial bore of substantially greater diameter than that of the arbor. The collars 20, hubs 23, and floating bosses 24 are of the same external diameter and they are 10 all provided with suitable coverings 25. Preferably, the floating bosses have only a limited freedom of rotary movement relative to the collars and hubs and, for this purpose, each boss is provided with pins 26, which project outwardly beyond its ends and are receivable in enlarged pockets 27 and 28 in the opposed ends of collars 20 and hubs 23, respectively. The floating bosses can be held against movement relative to the arbor by adjusting the collars 20 angularly about the arbor and securing them in position by set screws 21 with pins 26 clamped between the opposite sides of openings 27 and 28. When the parts are in this condition, the roll 18 operates in the manner of an ordinary top roll. If desired, the pins 26 may be omitted from the bosses, in which event the bosses will be rotated by contact with the stock being drafted and will not necessarily rotate in unison with the hubs, between which they lie.

An apron 29, made of leather or a suitable synthetic material, is led about the intermediate bottom roll 12, a nose bar 30 fixed in position in any suitable mounting, and a flanged tension roll 31 mounted in a bracket 32 attached to the roll stand. The nose bar is of generally triangular form and has a flat surface parallel to a plane tangent to the tops of the front and intermediate bottom rolls 11 and 12, so that the apron has a stretch 33 lying parallel to the path of the strand through the mechanism. The nose bar lies close to the nip of rolls 11 and 14 and a light self-weighted roll 34, having ends bearing against nibs on the cap bars, rests upon the apron above the nose bar.

A back saddle 35 bears against the neck of roll 15 between the bosses thereon and upon the neck 22 of roll 18. A front saddle 36 bears at one end against saddle 35 and, at the other end, against the neck of roll 14 between the bosses thereon. A stirrup 37 is connected to the front saddle 36 and a weighted lever 38 passes through the opening at the lower end of the stirrup. The lever has a nose attached to the roll beam 39 by a lever screw 40 and the weight 41 is connected to the opposite end of the lever by a hook 42.

The strand 43, which, in the case of a spinning frame, is a roving, is led from a bobbin in the creel through a trumpet 44 on the usual traverse bar 45 and between rolls 13 and 15, which grip it tightly. If the yarn is to be spun from double roving, the two rovings are drawn from their bobbins in the creel and led through the same trumpet. From rolls 13 and 15, the strand passes to the upper surface of the stretch 33 of the apron and beneath the floating boss 24 of roll 18. The strand lies in contact with the stretch 33 of the apron throughout the length of the stretch and passes beneath roll 34 to the front rolls 11 and 14.

In the operation of the new drafting mechanism described, the intermediate rolls 12 and 18 and apron 29 have a surface speed greater than the surface speed of the back or retaining rolls

13 and 15, as, for example, the surface speed of the intermediate rolls and apron may be about 1.30 times that of the retaining rolls, as is conventional in long draft mechanisms operating on cotton. However, the intermediate rolls and apron may be operated at a higher surface speed, if desired. The drawing rolls 11 and 14 are operated at a surface speed many times, for example, 16 or more, the surface speed of the back rolls. The roving is thus drafted between the back and front rolls and the floating boss 24 of the intermediate top roll and the self-weighted roll 34 press the roving against the apron for control purposes. The floating boss and roll 34 permit free passage of fibers, which are gripped by the drawing rolls 11 and 14 and advanced rapidly thereby, and at the same time control the trailing ends of such fibers. The floating boss and roll 34 restrain those fibers which are not gripped by the drawing rolls but would otherwise be drawn along by contact with fibers which are so gripped. The collar 20 and hub 23 on roll 18 press the edges of the apron tightly against the driven bottom roll 12, and the apron is thus advanced at the same surface speed as roll 12. If roll 18 were wholly floating and thus similar to the self-weighted roll 34, the apron would not be advanced at the proper rate merely by its contact with roll 12. On the other hand, if roll 18 were of the conventional construction and pressed tightly against the apron to advance it, the mechanism could not be used to draft roving of fibers having a staple length greater than the spacing between the nips of the front rolls 11 and 14 and intermediate rolls 12 and 18. With the construction described, therefore, provision is made for advancing the apron at the proper rate and, at the same time, that part of roll 18, namely, the floating boss 24, which engages the roving, merely controls the fibers therein.

As an indication of the superior performance of the new mechanism, the following test results may be given: A spinning frame equipped with the new mechanism was supplied with 2.00-hank roving made of a blend of 80% 3 denier 2" viscose and 20% 64s worsted top cut 2" with two ends of roving passing to each set of rolls. The roving was spun into an 18s/1 yarn, using a 3.50 twist multiplier and, since two ends of roving were supplied to each set of rolls, the draft was 18. The weight of the floating boss 24 of the intermediate top roll was 832 grains. The yarn so produced had a strength factor of 1396, whereas the best yarn produced from the same blend on a standard commercial frame designed for 2" staple and operating under the conditions above set forth, had a strength factor of 1320.

60 A 20s/1 yarn produced on a frame equipped with the new draft mechanism from double creel 2.00-hank roving of the blend above described with a draft of 20, using a twist multiplier of 3.50, had a strength factor of 1293. The best 20s/1 yarn produced on the standard commercial frame had a strength factor of 1220.

In the production of yarns in the tests above set forth, the surface speed of the apron was 1.30 times that of the back rolls but, since the floating boss 24 does not provide sufficient pressure to effect a break draft, it was found desirable to use a roving twist slightly lower than that which could have been used, if a break draft had been employed.

75 In conventional long draft mechanisms for

operation on cotton, the roving is gripped tightly by the back rolls, the intermediate rolls, and the front rolls, so that the distance between the nips of the front and intermediate rolls limits the maximum length of the fiber that can be handled. In such conventional mechanisms, it is necessary that the intermediate roll be weighted, in order that the single apron or the two aprons will be driven at the proper surface speed by the intermediate bottom roll. In the new drawing mechanism in the form shown in Figure 2, the use of the intermediate top roll with the floating boss makes it possible to apply sufficient pressure to the apron to insure that it will be driven at the proper surface speed by the intermediate bottom roll, but the relatively light floating boss applies only control pressure to the strand at the rear end of the active stretch of the apron and does not contribute to the drive of the apron. Accordingly, the mechanism can handle stock in which the fibers have a staple length only slightly less than the distance between the nips of the front and back rolls. A frame equipped with the floating boss roll may be converted to conventional long draft operation on short fibers merely by adjusting and setting the collar on the roll to clamp the floating boss and prevent it from floating. When the mechanism has been employed in such form, the conversion back to a form permitting the handling of long fibers requires only another adjustment and setting of the collar to free the boss and permit it to float.

I claim:

1. A drawing mechanism for use in textile frames having retaining rolls tightly gripping the strand to undergo draft and drawing rolls tightly gripping the strand and rotating at a surface speed substantially higher than that of the retaining rolls, the combination of an apron having a stretch lying beneath and parallel to the strand as it passes from the retaining rolls to the drawing rolls, said stretch of the apron supporting the strand in the drafting zone and being spaced from the nips of the retaining and drawing rolls, means for advancing the apron at a surface speed between those of the retaining and drawing rolls, said means including a driven roll within the apron and a roll having end portions pressing the edges of the apron tightly against the driven roll and a relatively light cylindrical central portion floating relatively to the end portions and adapted to rest upon and press the strand against the apron, a bar within the apron supporting it with the forward end of said stretch close to the nips of the drawing rolls, and a light roll adapted to press the strand against the apron above the bar, the light roll and said light central portion being operable to restrain fibers not gripped by the drawing rolls, while permitting free passage of fibers, which are gripped by the drawing rolls.

2. In a drawing mechanism for use in textile frames having retaining rolls tightly gripping the strand to undergo draft and drawing rolls tightly gripping the strand and rotating at a surface speed substantially higher than that of the retaining rolls, the combination of an apron having a stretch lying beneath and parallel to the strand as it passes from the retaining rolls to the drawing rolls, said stretch of the apron supporting the strand in the drafting zone and being spaced from the nips of the retaining and drawing rolls, and means for advancing the apron at a surface speed between those of the

retaining and drawing rolls, said means including a driven roll within the apron, a top roll having end portions pressing the apron tightly against the driven roll, a floating boss between the end portions and driven thereby, and means connecting the boss to the end portions for limited freedom of angular and radial movement relative to the end portions and operable to secure the boss rigidly to the end portions, the floating boss being operable to restrain fibers not gripped by the drawing rolls, while permitting free passage of fibers, which are gripped by the drawing rolls, and weighting means acting on said top roll.

3. In a drawing mechanism for use in textile frames having retaining rolls tightly gripping the strand to undergo draft and drawing rolls tightly gripping the strand and rotating at a surface speed substantially higher than that of the retaining rolls, the combination of an apron having a stretch lying beneath and parallel to the strand as it passes from the retaining rolls to the drawing rolls, said stretch of the apron supporting the strand in the drafting zone and being spaced from the nips of the retaining and drawing rolls,

25 a bar within the apron supporting it with the forward end of said stretch close to the nip of the drawing rolls, a driven roll within the apron at the rear end of said stretch thereof and having a surface speed between those of the retaining and drawing rolls, a top roll mounted above the driven roll and having end portions pressing the edges of the apron against the driven roll, a floating boss mounted between the end portions, and means connecting the boss and end portions to cause the boss to rotate with the end portions while having a limited freedom of angular and radial movement relative thereto, weighting means for said top roll, and a self-weighted roll lying above said stretch of the apron, said boss and self-weighted roll being adapted to press the strand against the apron to restrain fibers not gripped by the drawing rolls, while permitting free passage of fibers, which are gripped by the drawing rolls.

40 4. A roll for use in textile frames which comprises an arbor, end members mounted on the arbor in spaced relation, the end members having cylindrical surfaces concentric with the arbor and one member being fast on the arbor, while the second is angularly adjustable relative thereto, means for holding the second end member in selected angular relation to the arbor, a boss mounted on the arbor between the end members and having a cylindrical outer surface and a passage, through which the arbor extends, which is of substantially greater diameter than the arbor, and pins projecting beyond the ends of the boss axially thereof, the end members having openings in their opposed faces receiving the pins and of substantially greater diameter than the pins.
